UNITED STATES PATENT OFFICE

WILLIAM C. DEVEREAUX, OF DETROIT, MICHIGAN

LOCK CONSTRUCTION

Application filed May 10, 1926. Serial No. 108,168.

This invention relates generally to door locks and latches particularly designed for use upon the doors of vehicle bodies and consists of certain novel features of construction, combinations and arrangements of parts as will be more fully described and particularly pointed out in the appended claims.

In the accompanying drawings:

Figure 1 is a fragmentary side elevation of 10 a door latch embodying my invention;

Figure 2 is a fragmentary elevation of the opposite side of the door latch.

Figure 3 is a fragmentary perspective view 15 of the latch.

Figure 4 is a sectional view taken on the line 4—4 of Figure 1.

Referring now to the drawings, 1 is a case plate, 2 is a locking bolt, and 3 is a bolt shank 20 of a latch embodying my invention. As shown, the case plate 1 is provided at its forward edge with a laterally extending flange 4 having a suitable opening 5 that receives the bolt 2, while the latter is preferably formed 25 separate from the bolt shank 3 and is pivotally mounted on a pin 6 anchored in parallel flanges 7 projecting inwardly from the upper and lower edges of the opening 5.

As usual, the shank 3 is slidably mounted 30 on the case plate 1 and is provided at its forward end with a lateral flange or extension 8 for retracting the bolt. Heretofore such shanks were operatively connected to the pivoted bolts by separate pins that were anchored in the bolts in rear of the shank extensions 35 so as to be engaged thereby for retracting the bolts. In the present instance, however such pins have been dispensed with entirely. As shown, the side wings 9 of the bolt have inturned tongues 10 that are adapt-

40 ed to be engaged by the lateral extension 8 of the shank to retract the bolt. Any suitable means such as the helical spring 11 may be used to normally hold the shank 3 in its forward position, while any suitable means such

45 as the coil spring 12 may be used to normally hold the bolt 2 in projected position. As shown, the helical spring 11 is anchored on the case plate 1 and has an upstanding arm 13 that engages a wall of a suitable recess 14 in the shank 3, while the coil spring 12 is

sleeved upon the pin 6 and has the forward and rearward arms 15 and 16 respectively that bear against the bolt 2 and case plate 1.

For retracting the bolt I have provided a rollback 18 and a vertical spindle 19. As 55 shown, the rollback 18 has a hub 20 journaled in the case plate 1 adjacent to the lateral flange 4 and has an upstanding arm 21 that is engageable with an upstanding arm or projection 22 on the shank 3, while the spindle 60 19 is preferably mounted for rotary and rectilinear movement between the case plate 1 and cover plate 1' and is provided intermediate its ends with the crank portion 26 that is engageable with a lateral lug or projection 65 27 at the rear end of the shank 3. As shown, the case plate 1 is provided with the vertically spaced arcuate embossed portions 24 and 25 respectively and the cover plate 1' is 70 provided with the vertically spaced arcuate embossed portions 24' and 25'. When the parts are assembled as shown in Figure 1, the embossed portions 24' and 25' register with the respective embossed portions 24 and 25 and thereby form bearings A and B respectively in which the spindle is adapted to rotate or slide longitudinally. Any suitable means (not shown) may be engaged with the hub 20 of the rollback for actuating the latter from the outside of the door, while a suitable handle (not shown) may be connected to the upper end of the spindle 19 to actuate the same from the inside of the door. Preferably a coil spring 28 is used to normally retain the crank portion 26 of the spindle in operative position. This spring also effectively prevents the spindle from rattling.

In order that the outside bolt retracting means may be rendered inoperative from the inside of the door, I have provided a suitable 90 dog 29 that is pivoted on the case plate 1 between the spindle 19 and rollback 21 so as to be actuated by the former to prevent bolt retracting movement of the latter. As shown, this dog 29 is adapted to swing downwardly 95 into the path of the rollback and is provided at its rear end with a rearwardly extending lug or projection 30. Pivotedly mounted on the case plate 1, preferably at a point between the dog 29 and spindle 19, is a rocker 31 that

is provided at its opposite ends with the open ended slots 32 and 33 respectively. As shown, the forward slot 32 receives the lug 30 on the dog 29, while the rear slot 33 receives a ring 34 anchored on the spindle 19. Thus the rocker 31 may be actuated by a rectilinear movement of the spindle 19 to swing the dog 29 about its pivot to operative or inoperative positions.

10 In use, the dog 29 is normally in raised inoperative position and the bolt 2 may be retracted by either swinging the rollback arm 21 rearwardly against the shank projection 22 or by swinging the crank portion 26 of the 15 spindle rearwardly against the lug 27 on the shank. When it is desired to render the rollback inoperative, the spindle 19 may be pressed downwardly in the vertically spaced bearings A and B so that the ring 34 will cause the rocker 31 to lower the forward end of the dog 29 into the path of the rollback arm 21. When in this position, the rollback may be released by lifting the spindle 19 in the vertically spaced bearings A and B so 20 that the ring 34 will cause the rocker 31 to raise the forward end of the dog 29 out of the path of the rollback arm 21. Thus the dog 29 may be controlled and rendered effective or ineffective by the manipulation of 25 the inside bolt retracting means. The ring 34 is always free to turn in the slot 33 in the rocker and in slot 40 in case plate 1, hence the spindle 19 may be used to retract the bolt when in either raised or lowered positions.

30 If desired, a leaf spring 35 may be used to yieldably retain the spindle 19 in raised position. As shown, the upper end of this spring 35 is rigidly secured to the back of the case plate 1, while the lower end is provided 35 with a lateral lug or projection 36 that is engageable with a suitable groove 37 in the spindle 19.

While it is believed that from the foregoing description, the nature and advantage of 40 my invention will be readily apparent, I desire to have it understood that I do not limit myself to what is herein shown and described and that such changes may be resorted to when desired as fall within the scope of what 45 is claimed.

What I claim as my invention is:

1. In a lock, the combination with a bolt retracting member, of a second bolt retracting member mounted for rectilinear movement, and means for dogging the first member including an element engageable with the first member, and actuating means for said element including a rocker having a slotted connection with said element, and a part carried by the second mentioned retracting member engageable with said rocker.

2. In a lock, the combination with a bolt retracting member, of a second bolt retracting member mounted for rectilinear movement, 55 means for retaining the first member inop-

erative including a pivoted dog engageable with the first member and having an extension in rear of its pivot, and means for actuating said dog including a separate member operatively connected to the second bolt retracting member and engageable with said extension.

3. In a latch, the combination with a bolt retracting member, of a second bolt retracting member mounted for rectilinear movement, and means for dogging the first member including a pivotally mounted element engageable with the first member and having an extension, a ring secured to the second bolt retracting member, and a rocker having slots respectively receiving said extension and ring.

4. In a latch, the combination with a bolt retracting member, of a second bolt retracting member mounted for rectilinear and rotary movement, and means for rendering the first member inoperative including a dog engageable with the first member, a ring anchored on the second member, and a rocker terminally connected to said dog and ring.

5. In a latch, the combination with a bolt retracting member of a second bolt retracting member mounted for rectilinear and rotary movement, and means for rendering the first member inoperative including a pivotally mounted dog engageable with the first member and having a projection in rear of its pivot, a ring anchored on the second member, and a rocker having a slotted connection with said projection and ring.

6. In combination, a pivotally mounted hollow latch having substantially parallel side wings provided with inturned projections, and a slidably mounted shank extending into said hollow latch and having a lateral extension engageable with the inturned projections of said side wings to actuate the bolt.

7. In a latch, the combination with a case plate, and a bolt retracting member carried thereby, of a second bolt retracting member mounted for rectilinear movement on said case plate, a dog pivoted on the case plate for rendering the first mentioned member inoperative, and actuating means for the dog including a part pivoted on the case plate between said dog and second mentioned member and operable by a rectilinear movement of the latter.

8. In a latch, the combination with a case plate, and bolt retracting members spaced longitudinally thereof, and a dog pivoted on the case plate for rendering one of said members inoperative, of actuating means for the dog including an element carried by the other of said members, and a pivotally mounted part having slotted connections with both said dog and element.

9. In a latch, the combination with a pair of bolt retracting members, means for render-

ing one of said members inoperative including a dog movable into the path of said member, an element carried by the other of said members, and an intermediate element terminally connected to the dog and element aforesaid, the last mentioned element being mounted intermediate its ends for pivotal movement.

10 In testimony whereof I affix my signature.
WILLIAM C. DEVEREAUX.
